FOLDABLE PRAYER RAIL

Argo E. Landau, St. Louis, Mo., assignor to Royal Bond, Inc., St. Louis, Mo., a corporation of Missouri

Application January 3, 1949, Serial No. 68,978

9 Claims. (Cl. 155—166)

1

This invention relates to prayer rails and, more particularly, to certain new and useful improvements in portable kneeling rails.

An important object of the present invention is to provide a portable prayer rail of simple, compact and economical construction which is capable of being folded into a compact form for packaging, storage, or for being carried from place to place, as the case may be.

It is also an object of the present invention to improve on the construction and arrangement of prayer rails generally and to provide such an arrangement of parts therefor that the folding or erecting operation can be effected quickly and conveniently in a single manually controlled operation.

Another object of this invention may be found in the character and operating nature of the mechanism herein preferred for accomplishing the simultaneous folding or erecting operation and in the arrangement of elements to afford a positive, but easily releasable, retention of the prayer rails in erected position.

With the above and other objects in view, my invention resides in the novel features of form, construction, arrangement, and combination of parts presently described and pointed out in the claims.

In the accompanying drawings (three sheets)—

Figure 1 is a perspective view of a portable prayer rail in extended or serviceable position constructed in accordance with and embodying the present invention;

Figure 2 is a perspective view of the prayer rail in folded or collapsed position;

Figure 3 is a top plan view of the prayer rail in extended position;

Figure 4 is a fragmental front elevational view of the prayer rail in extended position;

Figure 5 is an end elevational view of the prayer rail with a frame housing end cover removed to show the important details of the folding mechanism therefor;

Figures 6, 7, 8, 9, 10, and 11 are transverse sectional views taken along lines 6—6, 7—7, 8—8, 9—9, 10—10, and 11—11, respectively, of Figure 5;

Figures 12 and 13 are fragmentary transverse sectional views taken along line 12—12 of Figure 11, showing the toggle joint in unlocked and locked positions; and

Figure 14 is an end elevational view of the prayer rail with a frame housing end cover removed to show the folding mechanism when the prayer rail is in folded or collapsed position.

Referring now by reference characters to the

2

drawings, which illustrate a preferred embodiment of my invention, A designates a prayer rail comprising two spaced similar end housings *h* on which have been mounted for pivoting movement an arm rest member 1 and a kneeling board 2. The assembled relationship of the housings *h*, arm rest member 1, and kneeling board 2 is such as to permit a smooth and rapid movement from the fully opened position shown in Figure 1 to the compact folded or collapsed position shown in Figure 2.

The end housings *h* of the prayer rail A are integrally formed or cast to provide an inner side wall 3, front and rear end walls 4 and 5, and a top wall 6 covering the forward and central portions of the housings *h*, said top wall 6 being extended upwardly, as at 8, centrally of the housings *h*. An outer side wall, in the nature of a removable cover 7, is secured to the respective walls 4, 5, and 6 in any desired manner. Thus, each housing *h* defines an interior space which is open along the bottom side, as at *x*, and along the top side rearwardly of the wall 6, as at *y*, and is readily adapted to receive and enclose foldable parts of the assembly and the folding mechanism presently to be described.

Rigidly mounted, at one end, in the inner wall 3 of each housing *h* and extending across the interior space for opposite end support in a suitable recess formed in the removable cover 7 are pivot pins 9, 10, for swingably supporting legs 11, 12, respectively, which are, in turn, provided with longitudinal recesses 13, 14. The rear wall 5 of each housing *h* is provided with a pair of internally threaded, vertically aligned apertures 15, 16, for receiving adjustment screws 17, 18, respectively, which may be threaded to project at their forward ends into the interior space of the housings *h* for reasons more fully appearing herein-after.

The arm rest member 1, positioned between the housings *h* adjacent the rear ends thereof, comprises a rectangular panel 19 having an artistic design 20 suitably provided thereon and being further provided about its margins with a rearwardly turned flange 21. Suitably secured to the flange 21 on the upper transverse margin of the panel 19 is a transversely extending arm rest 22, which may, if desired, be appropriately covered or upholstered. Secured by screws 23 to the lower end of each vertical flange 21 is a hinge element 24 integrally provided with a forwardly extending boss 25 having a longitudinal recess 26. The bosses 25 respectively project through the top openings *y* of the housings *h* and

are pivotally held in place by pins 27 which are supported at their ends in, and extend between, the wall 3 and the cover 1. When the hinges 24 are swung outwardly of the housings *h*, the end surfaces thereof will ordinarily abut the upper surfaces of the rear walls 5 and thereby hold the member 1 in a plane substantially at right angles to the longitudinal axes of the housings *h*, as best seen in Figure 5. It will be noted, however, that the adjustment screws 17, 18, will abut against the legs 11 and hinge elements 24, respectively, on being threaded forwardly through the apertures and thus act as adjustable stop means for varying the relative position of said leg 11 and member 1.

The kneeling board 2 is swingably mounted between the forward ends of the housings *h* and is suitably mounted at its ends on angle sections 28 having depending flanges 29 integral therewith for operative engagement with hinge pins 30, which are, in turn, rigidly mounted in the housing walls 3 whereby to permit pivotal movement of the kneeling board 2 between a rearwardly directed or kneeling position, as shown in Figure 5, and a forwardly swung or collapsed position, as shown in Figure 14. The two positions of the kneeling board 2 are determined by the action of a toggle link 31, spaced inwardly from the wall 3, and being pivotally connected at its forward end to the boss 29 by a pin 32 and connected at its rearward end to a V-shaped rocker member 33, as will now be more fully described.

Referring to Figure 5 in particular, the mechanism located in the end housing *h* for permitting folding or erecting movement of the arm rest member 1, kneeling board 2, and legs 11, 12, includes the rocker member 33, which has arms 34, 35, and is pivotally connected at its lower end or point of jointure of the arms 34, 35, by a pin 36 mounted in the walls 3, 7. The forward arm 35 of said member 33 is provided at its upper end with a relatively short transverse projection 37 extending through an arcuate slot 38 formed in the wall 3. Pivotally connected to the outer end of said projection 37 is the rearward end of the toggle link 31.

Disposed rearwardly of the rocker 33 within the housing *h* is a pair of spaced parallel short toggle links 39, 40, transversely connected in spaced parallel relation at their forward ends by a pin 41. Pivotally mounted at its rearward end upon the pin 41, intermediate the forward ends of the links 39, 40, is a toggle link 42, which is rockably connected at its forward end within the notch 14 of the leg 12, as by a pin 43 fixed therein.

At their rearward ends, the links 39, 40, are secured to a pin 44 extending transversely therebetween and projecting outwardly at its ends, which are received in suitable apertures in longitudinally extending spaced parallel links 45, 46. Mounted in the rearward ends of the links 45, 46, and extending therebetween is a pin 47 projecting at its inner end through and slidable in a longitudinal groove or slot 48 provided in the wall 3. Pivotally connected at their forward ends to the pin 47 inwardly of the links 45, 46, are links 49, 50, which are pivotally connected at their rearward ends, respectively, in the recesses 13, 26, of the legs 11 and the hinges 24, as by pins 51, 52, fixed therein respectively. Also pivotally mounted on the pin 47 within the housing *h* at its lower end is a leg 53 integrally joined at its upper end to a cover plate 54 de-

signed to be pivoted into a closurewise disposition between the upper margins of the walls 3, 7, rearwardly of the top wall 6 when the prayer rail A is in extended or serviceable position, as shown in Figure 5, and into concealed position within the housing 1 when the prayer rail A is in folded or collapsed position, as shown in Figure 14. The links 45, 46, are also pivotally connected at their forward ends on opposite sides of the upper end of the leg 12 by a pin 55.

In operation, the foregoing link mechanism will assume the position shown in Figure 14 when the arm rest member 1, the kneeling board 2, and the legs 11, 12, of both end housings *h* are in folded or collapsed position. In this folded position, it is to be noted that the arm rest member 1 is disposed between the upper margins of the walls 3 of the housings *h* and extends forwardly beyond said housings *h* in overlying relationship to the kneeling board 2, it being further noted that the legs 11, 12, and hinges 24 are disposed in concealed manner within the housings *h*, whereby the maximum degree of compactness is provided. To unfold or erect the prayer rail A, a lifting pressure is exerted on the arm rest member 1, causing it to be pivoted upwardly through action of the hinge elements 24, which pivoting effects a rearward movement of the links 45, 46, within the housings *h*. Such action causes the legs 11, 12, to be swung downwardly into operable position through extension of the connecting links 49, 42, respectively. It will be noted, as shown in Figure 5, that the pin 47 is at the extreme rearward end of the slot 48 when the arm rest 1 is fully unfolded, thereby serving as a detent to prevent further rearward movement of the link mechanism. Since the rocker member 33 is not connected to the link mechanism, the kneeling board 2 will still be, at this point, in collapsed position forwardly of the housings *h*.

The kneeling board 2 is then manually swung upwardly and rearwardly through approximately 180° from the position shown in Figure 14 to the position shown in Figure 5. This movement shifts the link 31 rearwardly and swings the V-shaped rocker member 33 rearwardly, causing the arm 35 thereof to bear down on the hinge pin 41 between the toggle links 39, 40, 42, thereby forcing the latter past dead-center position and locking the arm rest 1 and the legs 11, 12, in fully unfolded or serviceable position. In this position, the inner ends of the kneeling board 2 come to rest and are supported on bosses 56 formed integrally on the inwardly presented faces of the housing walls 3. The cover member 54 is disposed closurewise between the upper margins of the housing *h* forwardly of the top wall 6, so that the interior of the housing *h* is completely obscured from view of users of the prayer rail A.

In moving the prayer rail A from extended to folded position, the kneeling board 2 is swung reversely, whereby the inner face of the leg 34 of the rocker member 33 is swung upwardly against the hinge pin 41, causing it to move upwardly, thereby unlocking the link mechanism.

With the link mechanism in unlocked condition, downward and forward manual pressure applied on the arm rest member 1 will effect a downward pivoting of the hinge elements 24 about the pins 27, causing a simultaneous retraction of the links to effect a folding movement whereby the link mechanism is moved forwardly in the housings *h*, which causes the legs 11, 12, to be swung upwardly into the housings *h* and the member 1

to come to rest between the upper margins of the housings *h* in fully collapsed position.

The foregoing detailed description of a preferred kneeling rail construction and an operative foldable mechanism therefor will serve to illustrate the principal features of the invention in accordance with the stated objects.

It should be understood that changes and modifications in the form, construction, arrangement, and combination of the several parts of the prayer rail may be made and substituted for those herein shown and described without departing from the nature and principle of my invention.

Having thus described my invention, what I claim and desire to secure by Letters Patent is:

1. A prayer rail comprising a pair of end housings, front and rear legs pivotally mounted on each housing for movement between supporting and folded positions, an arm rest member pivotally connected to and disposed between the end housings for movement between erect and folded position, a toggle joint provided in each housing, linkage mechanism disposed in each housing for connecting the toggle joint with the arm rest member and the respective front and rear legs, and a rocker member pivotally mounted on each housing and adapted to engage the toggle joint for optional straightening and bending thereof whereby the arm rest member and the front and rear legs may be respectively locked in erect and supporting position or unlocked to facilitate folding movement.

2. A prayer rail comprising a pair of end housings, front and rear legs pivotally mounted on each housing for movement between supporting and folded positions, an arm rest member pivotally connected to and disposed between the end housings for movement between erect and folded position, a toggle joint provided in each housing, linkage mechanism disposed in each housing for connecting the toggle joint with the arm rest member and the respective front and rear legs, a rocker member pivotally mounted on each housing and adapted to engage the toggle joint for optional straightening and bending thereof whereby the arm rest member and the front and rear legs may be respectively locked in erect and supporting position or unlocked to facilitate folding movement, and a kneeling board operatively carried by and extending between the end housings.

3. A prayer rail comprising a pair of end housings, front and rear legs pivotally mounted on each housing for movement between supporting and folded positions, an arm rest member pivotally connected to and disposed between the end housings for movement between erect and folded position, a toggle joint provided in each housing, linkage mechanism disposed in each housing for connecting the toggle joint with the arm rest member and the respective front and rear legs, a rocker member pivotally mounted on each housing and adapted to engage the toggle joint for optional straightening and bending thereof whereby the arm rest member and the front and rear legs may be respectively locked in erect and supporting position or unlocked to facilitate folding movement, and a kneeling board pivotally mounted on and extending between the end housing, said board being operably connected to said rocker member for movement between a rearwardly directed serviceable position and a folded position.

4. A prayer rail comprising a pair of end 75 housings, front and rear legs pivotally mounted on each housing for movement between supporting and folded positions, an arm rest member pivotally connected to and disposed between the end housings for movement between erect and folded position, a kneeling board rockably mounted between the end housings for movement between operative and collapsed positions, actuating means disposed in each housing for connecting the arm rest member and the respective front and rear legs, and locking means operable responsive to movement of the kneeling board for optional engagement with the actuating means whereby the arm rest member and the front and rear legs may be respectively locked in erect and supporting position.

5. housings, front and rear legs pivotally mounted on each housing for movement between supporting and folded positions, an arm rest member pivotally connected to and disposed between the end housings for movement between erect and folded position, a toggle joint provided in each housing, linkage mechanism disposed in each housing for connecting the toggle joint with the arm rest member and the respective front and rear legs, a rocker member pivotally mounted on each housing and adapted to engage the toggle joint for optional straightening and bending thereof whereby the arm rest member and the front and rear legs may be respectively

10 locked in erect and supporting position or unlocked to facilitate folding movement, a kneeling board pivotally mounted on and extending between the end housing, said board being operably connected to said rocker member for movement between a rearwardly directed serviceable position and a folded position, and means operably connected to the linkage mechanism for closurewise disposition between the upper margins of the housing when the toggle joint is in straightened position.

15 5. A prayer rail comprising a pair of end housings, front and rear legs pivotally mounted on each housing for movement between supporting and folded positions, an arm rest member pivotally connected to and disposed between the end housings for movement between erect and folded position, a toggle joint provided in each housing, linkage mechanism disposed in each housing for connecting the toggle joint with the arm rest member and the respective front and rear legs, a rocker member pivotally mounted on each housing and adapted to engage the toggle joint for optional straightening and bending thereof whereby the arm rest member and the front and rear legs may be respectively locked in erect and supporting position or unlocked to facilitate folding movement, and a kneeling board operatively carried by and extending between the end housings, said kneeling 20 board being engageable with the toggle joint to lock same.

30 6. A prayer rail comprising a pair of end housings, front and rear legs pivotally mounted on each housing for movement between supporting and folded positions, an arm rest member pivotally connected to and disposed between the end housings for movement between erect and folded position, a kneeling board rockably mounted between the end housings for movement between operative and collapsed positions, actuating means disposed in each housing for connecting the arm rest member and the respective front and rear legs, and locking means operable responsive to movement of the kneeling board for optional engagement with the actuating means whereby the arm rest member and the front and rear legs may be respectively locked in erect and supporting position.

35 7. A prayer rail comprising a pair of end housings, front and rear legs pivotally mounted on each housing for movement between supporting and folded positions, an arm rest member pivotally connected to and disposed between the end housings for movement between erect and folded position, a kneeling board rockably mounted between the end housings for movement between operative and collapsed positions, actuating means disposed in each housing for connecting the arm rest member and the respective front and rear legs, and locking means operable responsive to movement of the kneeling board for optional engagement with the actuating means whereby the arm rest member and the front and rear legs may be respectively locked in erect and supporting position.

able responsive to movement of the kneeling board for operating the locking means.

8. A prayer rail comprising a pair of end housings, front and rear legs pivotally mounted on each housing for movement between supporting and folded positions, an arm rest member pivotally connected to and disposed between the end housings for movement between erect and folded position, a kneeling board rockably mounted between the end housings for movement between operative and collapsed positions, a toggle joint provided in each housing, linkage mechanism disposed in each housing for connecting the toggle joint with the arm rest member and the respective front and rear legs, a rocker member pivotally mounted on each housing and actuated by the kneeling board for engagement with the toggle joint for optional straightening and bending thereof whereby the arm rest member and the front and rear legs may be respectively locked in erect and supporting position or unlocked to facilitate folding movement, and a kneeling board operatively carried by and extending between the end housings.

9. A prayer rail comprising a pair of end housings, front and rear legs pivotally mounted on each housing for movement between supporting and folded positions, an arm rest mem-

ber pivotally connected to and disposed between the end housings for movement between erect and folded position, a toggle joint provided in each housing, linkage mechanism disposed in each housing for connecting the toggle joint with the arm rest member and the respective front and rear legs, a V-shaped rocker member pivotally mounted on each housing and embracingly disposed around the toggle joint for optional straightening and bending thereof whereby the arm rest member and the front and rear legs may be respectively locked in erect and supporting position or unlocked to facilitate folding movement, and a kneeling board operatively carried by and extending between the end housings.
